[57] CLAIM

The ornamental design for a riflescope mount, as shown and described.

DESCRIPTION

FIG. 1 is a perspective view of the new riflescope mount showing my new design;

FIG. 2 is a rear elevational view thereof;

FIG. 3 is a front elevational view thereof;

FIGS. 4 and 5 are elevational side views thereof, with the two views differing only in which end of a connecting bolt is visible;

FIG. 6 is a top view thereof; and

FIG. 7 is a bottom view thereof.

FIG. 1

FIG. 2

FIG. 3

FIG. 4

FIG. 5

FIG. 6

FIG. 7
